UNITED STATES PATENT OFFICE.

JAMES S. THOMPSON, OF PELHAM, NEW YORK, ASSIGNOR TO THE AMERICAN BRAKE SHOE AND FOUNDRY COMPANY, OF WILMINGTON, DELAWARE, A CORPORATION OF DELAWARE.

BRAKE SHOE.

1,402,117.

Specification of Letters Patent. Patented Jan. 3, 1922.

Application filed December 17, 1919. Serial No. 345,533.

To all whom it may concern:

Be it known that I, JAMES S. THOMPSON, a citizen of the United States, residing at Pelham, in the county of Westchester and 5 State of New York, have invented certain new and useful Improvements in Brake Shoes, of which the following is a specification.

This invention relates to improvements in 10 brake shoes and more particularly to that type in which the body metal is cast upon a plurality of strips, or a bundle, of expanded metal, or wire mesh, or other binding, bonding, or reinforcing reticulated metal arranged on edge to the wearing face 15 of the shoe and more broadly set forth in my companion application, Serial No. 345,532, filed concurrently herewith.

The object of the invention is to provide 20 for the assembly of inserts with the reticulated metal strips and in a simple and effective manner to properly position these parts with respect to each other for embedment in the cast body of the shoe.

25 In the accompanying drawings—

Fig. 1 is a side elevation, partly in section, illustrating one form of my present invention.

30 Fig. 2 is a cross sectional view on the line 2—2 of Fig. 1.

Fig. 3 is a view similar to Fig. 1, showing another form of the invention.

Fig. 4 is a cross sectional view on the line 4—4 of Fig. 3.

35 Fig. 5 is a view similar to Figs. 1 and 3, showing another form of the invention.

Fig. 6 is a cross sectional view on the line 6—6 of Fig. 5.

Referring to the drawings, the body 7 is 40 preferably provided with a suitable reinforcing and strengthening ductile metal back 8 which may be made in any of the variety of different ways well known in the art.

45 A plurality of reticulated metal strips are arranged on edge to the wearing face of the shoe and spaced apart between the sides of the shoe. These strips 9 may consist of commercial expanded metal, or wire mesh, or other suitable reinforcing reticulated metal may be used as set forth in my application above referred to. The strips are arranged in the shoe with their openings in registration and insert sections or blocks 10 are arranged in alternate open-

ings of the strips as shown in Fig. 1 or in Fig. 3, or they may be arranged in all of the openings as shown in Fig. 5. The strips are also preferably inclined on edge to the wearing face of the shoe, as clearly shown 60 in the cross section views, and this is particularly advantageous in the assembly of inserts with expanded metal strips, because the openings of the strips will register better when the strips are thus inclined and 65 permit the inserts to be inserted more readily into the openings. If the strips are arranged in an upright position perpendicular to the wearing face of the shoe, as they may be, it will be a little more difficult to insert 70 the insert sections or blocks, but this can be done and very satisfactory results achieved by this arrangement. However, I prefer the inclined or tilted arrangement 75 because it not only facilitates the assembling of the insert sections or blocks, but the position of the exposed parts of the strips on the wearing face of the shoe changes as the shoe wears down and thereby avoids any chance there may be of the strips scoring 80 or cutting the wheel.

My invention provides for assembling these strips and the insert sections or blocks easily and quickly into proper relation to form a single insert which is placed in the 85 mold with the reinforcing back to have the body metal cast thereon. The engagement of the insert sections or blocks with the strips will hold the strips in proper spaced relation and in proper position, whether it 90 be inclined or upright, and when the body is cast thereon, the several parts will be interlocked and interengaged in a secure and rigid manner so that if the shoe should be fractured, the parts thereof will be held together 95 so that the shoe may continue in service and without falling apart. The strips may be spot welded or otherwise suitably secured to the reinforcing back if found desirable. It depends upon the size and shapes of the insert sections or blocks and the mesh of the strips whether the inserts can be arranged in the strips as shown in 100 Figs. 3 and 5 or whether some distortion of the strips will be necessary to accommodate the inserts as shown in Fig. 1, and this is true whether expanded metal strips as 105 shown in the drawings are used or wire mesh, or other reticulated metal strips are used.

The insert sections or blocks may be made of any desired metal or material and in any shape adapted for the purpose. When they are arranged in alternate openings of the strips as shown in Figs. 1 and 3 their outer faces will lie substantially in a plane parallel with the wearing face of the shoe; but when they are arranged in all of the openings as shown in Fig. 5 they are in staggered relation in two series with the outer face of each series substantially in a plane parallel with the wearing face of the shoe.

It will be understood by those skilled in the art that my present invention may be adapted for and embodied in brake shoes of all known varieties and in different ways suitable for the many different conditions which prevail in the commercial use thereof. I believe that the several forms herein selected for illustrating the invention will sufficiently indicate its general objects and construction, but I reserve the right to make all such changes in the form, construction and arrangement of parts as fairly fall within the scope of the appended claims.

I claim:

1. A brake shoe comprising a plurality of reticulated metal strips arranged on edge to the wearing face of the shoe and having registering openings, insert sections or blocks arranged in said openings transversely of the strips, and a body cast on the strips and insert sections or blocks.
2. A brake shoe comprising a plurality of expanded metal strips arranged on edge to the wearing face of the shoe and having registering openings, insert sections or

blocks arranged in said openings transversely of the strips, and a body cast on the strips and insert sections or blocks.

40

3. A brake shoe comprising a plurality of reticulated metal strips arranged in an inclined position on edge to the wearing face of the shoe and having registering openings, insert sections or blocks arranged in said openings, and a body cast on the strips and insert sections or blocks.

45

4. A brake shoe comprising a plurality of expanded metal strips arranged in an inclined position on edge to the wearing face of the shoe and having registering openings, insert sections or blocks arranged in said openings, and a body cast on the strips and insert sections and blocks.

50

5. A brake shoe comprising a plurality of reticulated strips spaced apart on edge to the wearing face of the shoe and having registering openings, insert sections or blocks arranged in said openings transversely of the strips and in staggered relation, and a body cast on the strips and insert sections or blocks.

55

6. A brake shoe comprising a reinforcing back and a plurality of reticulated metal strips secured to said back in an inclined position on edge to the wearing face of the shoe and having registering openings, insert sections or blocks arranged in said openings, and a body cast on said back, strips and insert sections or blocks.

60

JAMES S. THOMPSON.
